UNITED STATES PATENT OFFICE.

ADELBERT FOSS SARGENT AND RALPH DORAN FARRELL, OF GENESEO,
ILLINOIS.

TWO-WHEELED VEHICLE.

SPECIFICATION forming part of Letters Patent No. 293,094, dated February 5, 1884.

Application filed October 16, 1883. (No model.)

To all whom it may concern:

Be it known that we, ADELBERT F. SARGENT and RALPH D. FARRELL, of Geneseo, in the county of Henry and State of Illinois, have 5 invented certain new and useful Improvements in Two-Wheeled Vehicles; and we do hereby declare that the following is a full, clear, and exact description of the invention, which will enable others skilled in the art to which it applies to make and use the same, reference being had to the accompanying drawings, which form a part of this specification, and in which—

Figure 1 is a side view of our improved two-wheeled vehicle with one wheel removed. Figs. 2 and 3 are detail views of one of the rear cranks and its suspending-iron, and Fig. 4 is a perspective detail view of one of the front cranks and its surroundings.

20 Similar letters of reference indicate corresponding parts in all the figures.

Our invention has relation to that class of two-wheeled vehicles in which the body is suspended upon cranks, by which the horse-motion 25 may be reduced to minimum; and it consists in the improved construction, combination, and arrangement of parts of the same, as hereinafter more fully described and claimed.

In the accompanying drawings, the letter A 30 indicates the body, which is a phæton-body of the usual construction, having a raised seat, B, and a lower box, C, for the limbs of the passengers.

D are the wheels, journaled upon the ends 35 of the axle, to which the shafts E are clipped at their inner ends, and upon which the springs F, which are elliptical springs, are clipped. Two side bars, G, are clipped near their rear ends upon these springs, and the front ends of, 40 the side bars are hinged upon bolts H, which pass through the arms of a stirrup or shackle, I, having two or more sets of perforations, J, for the reception of said bolts, and through sleeves or eyes K, secured upon the upper sides 45 of the side bars. These stirrups or shackles are clipped upon the under side of a cross-bar, L, fastened between the shafts, and upon which the single-tree M is pivoted. A rod, N, turns in bearings O upon the lower front 50 edge of the body and forms at its ends two

cranks, P, the outwardly-turned ends of which turn in bearings Q, upon the under side of the front ends of the side bars, supporting the forward end of the body, and two elastic cushions, R, prevent the said rod from rattling when the 55 bearings become worn. The rear ends of the side bars are provided with two upwardly-curved irons, S, which form eyes T upon their forwardly-curved upper ends, which eyes form bearings for the outwardly-bent ends of two 60 cranks, U, formed by the ends of a rod, V, turning in bearings W upon the lower rear edge of the seat of the body, and provided with elastic cushions K. In this manner it will be seen that the body hangs suspended by 65 the cranks, and may swing upon the same, so that the motion of the horse, communicated to the shafts, will not reach the body, which will hang in the same position without regard to the position of the shafts; and it will also 70 be seen that the body being suspended from the side bars, which again in turn are fastened to the springs and hinged to the cross-bar, will remove the motion still farther from the body. It will also be seen that the center of gravity 75 of the body will always be at the same point over the springs, as the body swings upon the cranks, thus avoiding all possibility of breaking or shaking the springs by changing the direction in which the weight falls upon 80 them.

The shackles at the forward ends of the side bars are for the well-known purpose of changing the level of the body, according to the size of the horse.

We are aware, as shown in the statement of the invention, that two-wheeled vehicles have been made in which the body is suspended in cranks taking up the horse motion, and we do not claim such construction, broadly; but 85

What we claim is—

The combination of an axle, elliptic springs clipped to the axle, shafts clipped to the axle and having the usual cross-bar, side bars hinged at their forward ends to the cross-bars 95 and secured near their rear ends to the springs, upwardly-curved irons secured to the rear ends of the side bars and forming transverse eyes at their ends, a body having transverse bearings at its front and rear ends, and rods 100

rocking in said bearings and having their ends bent upward, forming cranks rocking with their ends in the eyes of the upwardly-curved irons and in bearings near the forward ends of 5 the side bars, as and for the purpose shown and set forth.

In testimony that we claim the foregoing as

our own we have hereunto affixed our signatures in presence of two witnesses.

ADELBERT FOSS SARGENT.

RALPH DORAN FARRELL.
